UNITED STATES PATENT OFFICE.

CHARLES J. CARLISLE, OF COLDWATER, MICHIGAN.

DOOR-OPENING MECHANISM.

Application filed August 5, 1926. Serial No. 127,379.

This invention relates to mechanism for opening doors and it is designed primarily for use in connection with garage doors, and similar doors of other enclosures.

5 It is an object of the invention to provide a yieldingly supported runway which, when depressed by the weight of a vehicle or other structure of the proper weight, will cause the door or doors to shift to open 10 position and to remain open as long as the operating structure is traveling through the door opening. Thereafter the mechanism will act to automatically close the door.

A further object is to provide mechanism 15 of this character which is simple and compact in construction and can be used in connection with either single or double doors or with doors movable along straight or curved lines.

20 A further object is to provide door operating mechanism which can be adjusted readily and which is easily accessible for the purpose of oiling or repairing the parts.

With the foregoing and other objects 25 in view which will appear as the description proceeds, the invention resides in the combination and arrangement of parts and in the details of construction hereinafter described and claimed, it being understood 30 that changes in the precise embodiment of the invention herein disclosed may be made within the scope of what is claimed without departing from the spirit of the invention.

In the accompanying drawings the preferred form of the invention has been shown.

In said drawings,

Figure 1 is an inside elevation of the door of an enclosure to which the present operating mechanism is applied, the runway being shown in section and the door being closed.

Figure 2 is an elevation showing the outer side of the closed door and runway.

Figure 3 is a section on line 3—3, Figure 45 1.

Figure 4 is a section on line 4—4, Figure 1.

Referring to the figures by characters of reference 1 designates the wall of an enclosure which can be a garage, a fence or the like and this wall has a door opening 2 normally closed by a door 3. The door is slidably mounted on a supporting rail 4 or can be movably supported in any other manner desired, whereby when the door is thrust to one side, it will uncover the door

opening. In some forms of doors the movement is along a straight line and in other forms the doors travel within the corner portions of the enclosure along curved lines. 60 The operating mechanism constituting the present invention can be used in connection with doors of either type and for this reason it has not been deemed necessary to show other than a door movable along a straight line. 65

Arranged within the lower portion of the door opening 2 is a runway formed of downwardly diverging sections 5 yieldingly supported at their upper ends by springs 6. 70 These springs are of sufficient strength to support the weight of the runway and can be adapted to yield when any additional weight is applied to the runway or when any weight over and above a predetermined 75 amount is applied to the runway. In other words the springs could be of sufficient strength to prevent actuation or depression of the runway under the weight of a person but would yield to permit depression of the 80 runway should a vehicle be moved onto the runway. It is to be understood that the runway can be of any suitable material, either wood, metal or slabs of concrete suitably reinforced. 85

Journalized within the enclosure at a point above one side portion of the door opening 2 is an elongated lever 7 the upper end of which is offset as at 8 and pivotally connected to the enclosure as shown at 9. That 90 portion of the lever adjacent the offset is provided with a notch 10 in which is seated the upper end of a connecting rod 11. This rod has its lower end attached to the runway 5 close to the uppermost portion thereof and if desired the connecting rod can be made up of two screw threaded sections connected by a turn buckle 12. 95

The lower end of the lever 7 which is normally supported laterally beyond the door opening 2 is formed with a longitudinal slot 13 and working in this slot is a stud 14 extending laterally from one of the end arms 15 of a lazy tongs 16. The other end arm 17 of the lazy tongs is connected to the arm 15 100 and to the enclosure 1 by means of a pivot bolt 18 or the like. That end of the lazy tongs 16 remote from the arms 15 and 17 is pivotally connected at 19 to the door 3. 105

The free end portions of the arms 15 and 17 are connected by a coiled spring 20, this spring serving to facilitate the elongation of 110

the lazy tongs during the closing of the door 3 as hereinafter explained.

Under normal conditions the door is closed as shown in Figures 1 and 2. When a vehicle moves onto the runway 5 while approaching the opening 2, said runway is depressed against the action of the springs 6 and pulls through the rod 11 upon the upper end portion of the lever 7. Thus the lever will be swung toward the door opening 2 and will thrust through stud 14 upon the lower arm 15 of the lazy tongs. This will result in elongation of spring 20 and contraction of the lazy tongs with the result that the door 3 will be pulled to an open position and be held open as long as the runway 5 supports the operating load. As soon as the load of the vehicle leaves the runway after passing through the opening 2, the springs 6 will be relieved of their compression and return the runway to its normal position. Thus rod 11 will tend to thrust upwardly upon lever 7 and at the same time spring 20 tends to restore the lazy tongs to its normal position. Consequently the door 3 will be thrust to closed position and the parts will be reset. By providing the spring supports for the runway 5 it is possible for a person to stand on the runway and push the door to open position, the lazy tongs exerting sufficient leverage against the lever 7 to cause rods 11 to thrust downwardly on the runway and produce the necessary relative movement of the runway and door.

The door operating mechanism can all be exposed upon the inner surface of the wall of the enclosure where the parts can be easily reached for greasing or repairing them but it will be understood of course that if desired these working parts can be housed within the wall. Where two doors are provided the mechanism already described is duplicated at the other side of the

door opening, one runway, however, serving to operate both mechanisms. This modification is so obvious that it is not deemed necessary to show the same in the drawings.

What is claimed is:

1. The combination with a structure having a door opening and a door slidably mounted to close the opening, of a runway extending through the lower portion of the door opening and under the path of the door, a lever fulcrumed to said structure and extending to one side thereof, said lever having an offset upper end portion pivotally connected to the structure, a lazy tongs pivotally connected to the door and to the structure, there being arms constituting one end of the lazy tongs, a slidable and pivotal connection between the lever and one of the arms, yielding means for shifting the arms toward each other, and a working connection between the runway and the upper end portion of the lever.

2. The combination with a structure having a door opening and a yieldingly supported runway extending through the lower portion of the opening, of a door mounted to slide, a lazy tongs pivotally connected to the door and to the structure, said tongs having superposed arms constituting one end portion thereof, yielding means for closing the arms toward each other, a lever having an offset upper end portion pivotally connected to the structure at a point above the door opening, a pivotal and slidable connection between the lower end portion of the lever and one of the arms of the lazy tongs, and an adjustable operating connection between the runway and the upper portion of the lever.

In testimony that I claim the foregoing as my own, I have hereto affixed my signature.

CHARLES J. CARLISLE.
